SASH OR STORE FRONT CONSTRUCTION

Clyde D. Lowry, Toledo, Ohio, assignor to Libbey-Owens-Ford Glass Company, Toledo, Ohio, a corporation of Ohio

Application May 29, 1937, Serial No. 145,438

7 Claims. (Cl. 20—56.4)

The present invention relates to a sash or store front construction.

More specifically, the invention pertains to that type of sheet or pane mounting means in which the glass is supported and clamped between two metal sections. Ordinarily, in such constructions there is a rigid rear member and an adjustable or movable face member between which the glass is held in position. It is quite common to hold the face member in proper association with the glass and rear member by means of screws passing through both the face member and rear member and extending into a suitable back stop.

The primary object of the present invention is to provide a design of mounting in which the adjusting means for the face member does not extend through the rear member and into the back stop. This is accomplished by employing anchor members preferably detachably associated with the fixed member and adapted to receive the inner end of the adjusting member which extends through the face piece. With such a construction, it is merely necessary to mount the fixed member upon the sill or other support and then, after arranging the glass sheet in position, place the face piece in operative relation and extend the adjusting members through the face piece and anchor member or plate. This gives a very flexible and satisfactory design of mounting.

In accordance with the invention, the so-called anchor members may be in the nature of relatively short metallic sections either formed integrally with the fixed section or as separate units easily mounted in place and having portions cooperating with the fixed section whereby upon receipt of the adjusting member extending through the face piece, the anchor plate will be locked in position and will firmly hold the face piece in adjusted relation with respect to the fixed member and pane of glass.

Other objects and advantages of the invention will become more apparent during the course of the following description when taken in connection with the accompanying drawings.

In the drawings wherein like numerals are employed to designate like parts throughout the same,

Fig. 1 is a diagrammatic view of a store front illustrating one use to which my improved construction can be put;

Fig. 2 is an enlarged vertical transverse section through a portion of the mounting;

Fig. 3 is a fragmentary perspective view, partially in section, showing a face piece and anchor member;

Fig. 4 is a vertical transverse section through a type of mounting designed for supporting a plurality of sheets of glass; and

Fig. 5 is a similar section through a common form of construction intended to be replaced by my improved design.

Referring more particularly to Fig. 1, the numeral 10 designates a sheet or pane of glass mounted in an opening of a building wall 11. The glass 10 is held in position by means of the 10 metal members 12 which will be more fully described hereinafter. As shown, a transom 13 is located above the sheet 10, and the transom glass can likewise be held in place by the same mounting as used in connection with the pane 10. It will of course be understood that this particular use is by way of illustration only as my improved glass mounting can be employed in other places such as showcases and the like.

In Fig. 5 is shown a common form of sash or store front construction in which a fixed section 14 rests upon the sill 15 and contacts a back stop 16 likewise carried by the sill. The sheet of glass 17 rests on its lower edge upon mounting blocks (not shown) and is held in place by means of the face piece 18 through which extends the screw 19 likewise extending through a suitable opening in the fixed member 14 and into the back stop 16.

The lower edge 20 of the face piece is received in a channel formed by the bottom portion 21 and spaced flange 22 carried by the fixed or rear section 14. This permits longitudinal bodily movement of the face piece to accommodate different thicknesses of glass. As can be readily seen, the face piece is held in position against the glass 17 by means of the wood screws 19 arranged at spaced intervals along the face piece and extending through both sections and being received in the back stop 16.

The use of such wood screws is objectionable for a number of reasons, among which are the difficulty of installation, necessity for accurate lining up the openings in the two sections, and danger of the wood screws from eventually becoming loose in the back stop 16, especially as the back stop ages resulting in dry rot or other deterioration. Furthermore, if the wood screw is removed for any reason or adjusted in or out after installation, the effectiveness of the device is reduced, totaling up to a decidedly unsatisfactory type of installation.

In accordance with the present invention, the use of wood screws or other adjusting member extending through both the face and rear mem-

bers and anchoring in a back stop or other device is entirely avoided.

Referring to Fig. 2, the rear section 23 rests upon the sill 24 and is permanently mounted in position by means of wood screws 25 screwed into the back stop 26. As in the case of Fig. 5, a face member 27 movably associated with the fixed member 23 is provided with the lower edge 28 received between the bottom portion 29 of the back member and spaced flange 30, serving to form a channel to permit bodily movement of the face piece toward and away from the rear member to permit accommodation of varying thicknesses of glass.

15 In the particular construction of the invention illustrated, the spaced flange portion 30 carries a rearwardly extending lip 31 so that the anchor member or plate 32 can be placed upon the upper surface of the flange 30 in a manner that the 20 overhanging hook end 33 may engage the lip 31 as shown. The anchor member is substantially L-shaped with the bottom portion resting upon the flange 30 and with the upright arm being provided with a threaded opening 34 to receive 25 the threaded end of the adjusting member 35 which may be in the nature of a bolt. The adjusting member 35 extends through an opening formed in the face piece 27 which is in proper alignment with the threaded opening 34 so that 30 the adjusting member may extend through the face piece and be received in the said threaded opening. As can be seen, upon adjustment of the member 35, the anchor plate 32 will be pulled toward the front piece until the hook member 33 is 35 in tight engagement with the lip 31, after which the face piece will be moved toward the fixed section thereby clamping the glass between the two sections.

If, as is preferred, the anchor plates are 40 detachable clamps which can be mounted upon the fixed section as required, they can be quite readily lined up so that the adjusting members can be put into operative position. By having the anchor members arranged for interlocking 45 engagement with a portion of the fixed member, the face piece can readily and accurately be adjusted to proper glass clamping position. An important feature of the use of the anchor members aside from ease of installation resides in 50 the elimination of the long wood screws such as indicated at 19 in Fig. 5.

In Fig. 4 is disclosed the same principle as applied to a sash mounting involving placement of a pair of spaced sheets of glass 36. Such a 55 construction is desirable in refrigerated showcases and for similar uses. In the particular design set forth, the rigid member 37 serves as a back for both movable sections 38 and 39. The anchor members 40 are associated with the fixed 60 member in exactly the same manner as just explained in connection with Fig. 2 and of course the adjusting members 41 are used to clamp the glass sheets in position. If used in refrigerated showcases, it may be desirable to seal the glass 65 as by means of a rubber gasket 42 to prevent loss of heat or passage of moist air in between the glass sheets thereby avoiding condensation.

It is to be understood that the form of the invention herewith shown and described is to be 70 taken as the preferred embodiment of the same, and that various changes in the shape, size and arrangement of parts may be resorted to without departing from the spirit of the invention or the scope of the subjoined claims.

75 I claim:

1. In a sash or store front construction, the combination of a fixed section and a movable section adapted to receive and grip a pane of glass therebetween, a flange portion having a rearwardly extending lip carried by the fixed section, an anchor member detachably associated with said flange portion and having a hook portion engaging said rearwardly extending lip, and an adjusting member extending through the movable section and anchor member to urge the sections into engagement with the pane of glass, said movable section and anchor member being removable without displacement of the pane of glass. 5

2. In a sash or store front construction, the combination of a fixed section and a movable section adapted to receive and grip a pane of glass therebetween, a flange portion having a rearwardly extending lip carried by the fixed section, an anchor member detachably associated with said flange portion and having a hook portion engaging said rearwardly extending lip, and a bolt extending through the movable section and anchor member to urge the sections into engagement with the pane of glass, said movable section and anchor member being removable without displacement of the pane of glass. 10

3. In a sash or store front construction, the combination of a fixed section and a movable section adapted to receive and grip a pane of glass therebetween, an anchor member detachably associated with and slidable longitudinally of the fixed section, and an adjusting member carried by the movable section and cooperating with the anchor member to urge the sections into engagement with the pane of glass, said movable section and anchor member being removable without displacement of the pane of glass. 20

4. In a sash or store front construction, the combination of a fixed section and a movable section adapted to receive and grip a pane of glass therebetween, an anchor member positioned within the movable section and having a portion adapted for detachable interlocking engagement with a portion of the fixed section, said anchor member being slidable longitudinally of the fixed and movable sections, and an adjusting member carried by the movable section and engageable with the anchor member to urge the sections into engagement with the pane of glass, said movable section and anchor member being removable without displacement of the pane of glass. 45

5. In a sash or store front construction, the combination of a fixed section and a movable section adapted to receive and grip a pane of glass therebetween, a substantially L-shaped anchor member mounted between the fixed and movable sections and slidable longitudinally with respect thereto and having a portion detachably interlocking with a portion of the fixed section, 60 and an adjusting member carried by the movable section and cooperating with the anchor member to urge the sections into engagement with the pane of glass, said movable section and anchor member being removable without displacement of the pane of glass. 65

6. In a sash or store front construction, the combination of a fixed section and a movable section adapted to receive and grip a pane of glass therebetween, a flange portion having a rearwardly extending lip carried by the fixed section, a substantially L-shaped anchor member associated with the said flange portion and having a hook portion detachably engaging said rearwardly extending lip, the anchor member 70

being slidable longitudinally upon the flange portion, and an adjusting member extending through the movable section and anchor member to urge the sections into engagement with the pane of glass, said movable section and anchor member being removable without displacement of the pane of glass.

7. In a sash or store front construction, the combination of a fixed section and a movable section adapted to receive and grip a pane of glass therebetween, a flange portion having a rearwardly extending lip carried by the fixed section, a substantially L-shaped anchor member

positioned between the fixed and movable sections, one arm of said member having a hook portion detachably engaging said rearwardly extending lip of the flange portion, the other arm of said L-shaped anchor member having a 5 threaded opening therethrough, and a bolt extending through the movable section and threaded opening in the arm of the anchor member for urging the sections into engagement with the pane of glass, said movable section and anchor member being removable without displacement of the pane of glass.

CLYDE D. LOWRY.
